US00D673683S

(12) **United States Design Patent**
McCormack et al.

(10) **Patent No.:** US D673,683 S
(45) **Date of Patent:** ** Jan. 1, 2013

(54) **MEDICAL DEVICE**

(75) Inventors: **Bruce M. McCormack**, San Francisco, CA (US); **Edward Fletcher Eyster**, Helena, CA (US); **Jeffrey D. Smith**, Clayton, CA (US); **Edward Liou**, Mountain View, CA (US); **Jonathan Carver**, Sausalito, CA (US); **Peter How**, Sunnyvale, CA (US); **Joshua Druker**, Redwood City, CA (US); **Martin Leugers**, San Francisco, CA (US); **Shigeru Tanaka**, Half Moon Bay, CA (US)

(73) Assignee: **Thayer Intellectual Property, Inc.**, San Francisco, CA (US)

(**) Term: **14 Years**

(21) Appl. No.: **29/369,905**

(22) Filed: **Sep. 15, 2010**

(51) LOC (9) Cl. **24-02**

(52) U.S. Cl. **D24/171; D24/133**

(58) **Field of Classification Search** D24/171, D24/133, 146, 147, 155, 188; D8/80, 83, D8/94, 97, 107, 303; 606/53, 79, 80, 167, 606/170, 114; 604/533

(57) **CLAIM**

The ornamental design for a medical device, as shown and described.

DESCRIPTION

FIG. 1 is a front perspective view of a medical device including a first handle and a second handle, wherein the second handle is shown as engaged with the first handle;

FIG. 2 is a rear perspective view of the medical device of FIG. 1;

FIG. 3 is a left side view of the medical device of FIG. 1;

FIG. 4 is a right side view of the medical device of FIG. 1;

FIG. 5 is a rear view of the medical device of FIG. 1;

FIG. 6 is a front view of the medical device of FIG. 1;

FIG. 7 is a top view of the medical device of FIG. 1;

FIG. 8 is a bottom view of the medical device of FIG. 1;

FIG. 9 is a front perspective view of the medical device of FIG. 1, wherein the second handle is shown as disengaged from the first handle;

FIG. 10 is a rear perspective view of the medical device of FIG. 1, wherein the second handle is shown as disengaged from the first handle;

FIG. 11 is a left side view of the first handle of the medical device of FIG. 1;

FIG. 12 is a right side view of the first handle of the medical device of FIG. 1;

FIG. 13 is a rear view of the first handle of the medical device of FIG. 1;

FIG. 14 is a front view of the first handle of the medical device of FIG. 1;

FIG. 15 is a top view of the first handle of the medical device of FIG. 1;

FIG. 16 is a bottom view of the first handle of the medical device of FIG. 1;

FIG. 17 is a left side view of the second handle of the medical device of FIG. 1;

FIG. 18 is a right side view of the second handle of the medical device of FIG. 1;

FIG. 19 is a rear view of the second handle of the medical device of FIG. 1;

FIG. 20 is a front view of the second handle of the medical device of FIG. 1;

FIG. 21 is a top view of the second handle of the medical device of FIG. 1; and,

FIG. 22 is a bottom view of the second handle of the medical device of FIG. 1.

The broken lines in the drawing views are included for the purpose of illustrating portions of the medical device that form no part of the claimed design.

1 Claim, 13 Drawing Sheets
